UNITED STATES PATENT OFFICE.

MORTON G. BUNNELL, OF CHICAGO, ILLINOIS, ASSIGNOR TO FREDERICK C. AUSTIN, OF SAME PLACE.

DUMPING-CAR.

SPECIFICATION forming part of Letters Patent No. 634,684, dated October 10, 1899.

Application filed February 17, 1899. Serial No. 705,856. (No model.)

To all whom it may concern:

Be it known that I, MORTON G. BUNNELL, a citizen of the United States, residing at Chicago, in the county of Cook and State of Illinois, have invented a certain new and useful Improvement in Dumping-Cars, of which the following is a specification.

Objects of my invention are to provide a simple and efficient construction of dumping-car involving a comparatively low-down, normally-balanced, easy-working, and self-righting car-body, to permit such car-body to dump at one side of the track, to simplify the arrangement of gates for opening and closing the dumping-receptacle formed by the tilting body, and to permit the body to tilt without tilting either of the gates employed, but at the same time to shift the gates sidewise synchronously with its bodily side movement, so as to maintain such gates in determinate relative positions suitable for closing the open sides of the body when the latter is righted or in its normal horizontal position.

To the attainment of the foregoing and other useful ends, the car-body forms a receptacle open at opposite sides and is supported by a rocker-base, which permits it to have a combined tilting and bodily side movement in dumping. When the body is righted or in its normal horizontal position, its open sides are closed by oppositely - arranged non-tilting gates, which are connected with the body, so that when the latter is operated for dumping the gates which are supported by the car-truck will move sidewise with and as a result of the bodily side movement of the body, but will not rise or partake of the tilting action of the body. In this way the gates are permanently down regardless of the position of the body and are at all times in place to close the sides of the body when the latter is righted or in its normal horizontal position.

In the accompanying drawings, Figure 1 represents in end elevation a dumping-car embodying the principle of my invention. Fig. 2 is a like view showing the car-body in position for discharging the load at one side of the car-track. Fig. 3 represents the car in side elevation.

The tilting car-body A, which is adapted to provide a suitable receptacle for the load,

is constructed with ends *a a* and a suitable bottom, but is open at its longitudinal sides—that is to say, the sides usually present in the tilting body and commonly formed by or involving movable side gates are not present. In place of such movable side gates I arrange as fixtures upon or part of an independent frame B a couple of oppositely-arranged and longitudinally - extending side gates C C, which are formed and positioned relatively to the tilting body to close the open sides of the latter and constitute sides or gates therefor when such tilting body is in its normal horizontal position, as in Fig. 1. The tilting body is arranged to tilt about a horizontal longitudinal axis passing through the center of each of its two ends, and for such purpose it is pivoted or trunnioned in transversely-arranged end bars or plates *b*, which, together with the gates C C, constitute a frame or carrier. The end edges of the end portions *a* of the tilting body swing in the arcs of a circle having as its center an axis passing centrally through the trunnions, and hence to adapt the gates C upon the carrier B to effectively close the open sides of the tilting body when the latter is in its normal horizontal position the gates C C and the end edges *a'* of the end portions *a a* of the tilting body are formed on curves corresponding with the arcs of said circle.

The frame or carrier B, which comprises and carries the gates, is arranged for horizontal side movement, either way, upon the car-track, and is preferably guided and supported by grooved rolls D, which engage and traverse suitably-formed guides or rails E extending transversely across the car-truck at or near the ends of the latter. These guides extend somewhat beyond the sides of the car-truck, so as to permit the carrier to be shifted to one side to an extent suitable to allow the car-body to be tilted for dumping the load at one side of the car-track, as illustrated in Fig. 2, in which it will be seen that while the axes of the trunnions are substantially over the wheels at one side of the car, or substantially in a plane occupied by such wheels, the tilted car-body is in position to discharge the load considerably at one side of the car-track.

The tilting car - body is provided with a

rocker-base having its curved bearing-face on the arc of a circle having as its center an axis extending centrally through the trunnions, the preferred arrangement being to divide the 5 rocker-base into two or more comparatively large rockers F, arranged to bear and rock upon the truck-frame. As a matter of simplification and further improvement the base-flanges e of the guide rails or bars E can provide 10 bearings for the rockers, and to avoid slip the rockers have notches f, corresponding with and adapted to receive teeth e' on the base-flanges of the bars E or the converse thereof, as may be desired.

15 The carrier B or the tilting car-body A can be provided with any suitable construction of latch or catch means for locking the tilting body in a horizontal position—as, for example, the carrier may have on each gate C a rock-shaft G, provided with catches g, which engage under the side-edges of the bottom of the tilting body when the latter is in a horizontal position. These catches can be normally maintained in position to thus engage 20 the tilting body by means of springs H, suitably applied to the rock-shafts, and the catches can be suitably beveled and arranged so that their action shall be automatic—that is to say, after the load has been dumped and the body 25 is tilted back to its normal horizontal position a side edge of its bottom will during such return movement of the body strike and momentarily force back the catches at one side of the carrier, so as to allow such edge of the 30 body-bottom to pass.

35 The tilting body is normally balanced whether empty or loaded, and when loaded it can be easily tilted as a result of its balanced condition, and by reason of the arrangement 40 hereinbefore described said tilting body will be comparatively low down when in a horizontal position, thereby permitting it to be loaded and manipulated with ease and also insuring safety during transportation. It 45 will also be seen that while the tilting body is thus set comparatively low down I attain a maximum extent of combined bodily side shift and tilting movement. In order to dump the load, it will only be necessary to unlock or unlatch the tilting body at one side 50 of the car either by manually operating the catch device at one side or by tilting the body with sufficient force to cause it to automatically operate such catch device, and thereby effect its release from therefrom. As 55 the weight of the tilting body is sustained by the car-truck intermediately through the rocker-base or rockers and as the rocker-base has its bearing face or faces on the arc of a circle of comparatively large radius, the body 60 can be easily tilted. When the tilting body is thus tilted, it will have a bodily side movement, combined with a tilting action, and will cause the laterally-shifting frame or carrier, 65 which is provided with the gates C C, to move to one side to an extent proportional to the bodily side movement of the tilting body.

When the tilting body is thus tilted, it leaves the said gates C C as in Fig. 2, and hence it will open and discharge the load. After dumping the tilting body will right itself, it being seen by Fig. 2 that after the discharge the greater portion of the weight of the tilting body will be between a vertical plane passing centrally through its trunnions and the middle portion of the car-truck. In this way little or no help will be required in righting the car-body, which latter in tilting back to a horizontal position will cause the carrier to shift back in place upon the car-truck. 70

75 With further reference to the means herein employed for opening and closing the sides of the tilting car-body it will be seen that the gates C C, which close the tilting body when the latter is in a horizontal position, 80 are connected together by the end bars or frame parts b and are non-tilting and that these members C and b constitute a rigid or substantially rigid frame or carrier adapted as a whole for horizontal side shift simultaneously with and as a result of the action of the 85 tilting body, which is pivotally connected with such frame or carrier. In this way the gates C, which serve to close the body when the latter is in a horizontal position, have no 90 effect upon the tilting action of the body, which tilts independently of the gates, and hence said gates will in no wise tend to retard such action and will not overweight the body at one or the other side while it is being 95 tilted for the purpose of dumping the load. This arrangement also admits of an extremely 100 simple construction.

105 What I claim as my invention is—

1. A dumping-car comprising a body forming a receptacle open at opposite sides and supported by a rocker-base so as to have a combined tilting and bodily side movement in dumping; and oppositely-arranged non-tilting, laterally-movable gates relatively positioned to close the open sides of the body when the latter is in its normal, horizontal position; the body being connected with the gates to tilt independently thereof but cause them to partake of its bodily side movement, 115 substantially as described.

2. A dumping-car comprising a body forming a receptacle open at opposite sides and supported by a rocker-base so as to have a combined tilting and bodily side movement 120 in dumping; and a frame or carrier supported to move sidewise upon the truck-frame and comprising a pair of non-tilting gates arranged for closing the open sides of the body when the latter is in its normal, horizontal 125 position; the body being pivotally connected with said frame or carrier at points on a line passing substantially through the center of each of its ends, substantially as described.
